[57] **CLAIM**

The ornamental design for a track light housing, as shown and described.

DESCRIPTION

FIG. 1 is a front, right side and upper perspective view of a track light housing showing my new design;

FIG. 2 is a front elevational view thereof;

FIG. 3 is a rear elevational view thereof;

FIG. 4 is a top plan view thereof;

FIG. 5 is a right side elevational view thereof;

FIG. 6 is a bottom plan view thereof; and,

FIG. 7 is a left side elevational view thereof.

The yoke and transformer housing are shown in broken lines for illustrative purposes only.

FIG. 2

FIG. 3

FIG-4FIG-5FIG-6FIG-7
